Attorney

UNITED STATES PATENT OFFICE.

FREDERICK J. LAU, SR., OF WATERBURY, CONNECTICUT.

COMBINATION SHOE STRETCHER AND TREE.

Application filed July 5, 1927. Serial No. 203,567.

The present invention relates to a combination shoe stretcher and tree and has for its principal object to provide an exceedingly simple structure that may be manufactured at a low cost, is thoroughly efficient and reliable in use, durable, convenient, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

15 In the drawing:

Figure 1 is a plan view of the device showing the manner in which the same is used,

Figure 2 is a transverse section therethrough taken substantially on the line 2—2 of Figure 1,

Figure 3 is a view similar to Figure 1 showing the device in a closed position.

Referring to the drawing in detail it will be seen that the letter R denotes a single spring rod which is bent intermediate its ends into a substantial U-shaped formation to include a bight portion and a pair of arms 6 the extremities of which are curved inwardly toward each other as at 7. The numeral 8 denotes a loop formed from a strand of material having its ends bent over upon itself for forming loop portions to receive the arms 6. A handle and hanger member 9 has an eye at one end as at 10 to engage the loop 8 intermediate its ends and an eye 11 at the other end so that the structure may be hung up when it is to function as a tree.

When the loop is disposed as shown in Figure 3 it will be seen that the device is con-

tracted so that it may be easily placed in a shoe and then the loop may be slid toward the bight so that the device will expand, that is the curved extremities 7 of the arms or legs 6 will move away from each other and tend to stretch the shoe.

It is thought that the construction, utility, and advantages of this invention will be quite apparent without a more detailed description thereof. The present embodiment of the invention has been disclosed in detail merely by way of example since in actual practice it attains the features of advantage enumerated as desirable in the statement of the invention and the above description. It will be apparent that changes in the details of construction may be resorted to without departing from the spirit or scope of the invention as hereinafter claimed or sacrificing any of its advantages.

Having thus described my invention, what I claim as new is:—

A device of the class described comprising a strand of spring material bent over upon itself intermediate its ends to a substantial U-formation to include a bight and a pair of legs diverging normally from each other from the bight and terminating in inwardly curved end portions, and means for urging the curved extremities of the legs toward each other, said means comprising a loop receiving the legs and slidably thereon, a handle and hanger member comprising an eye at one end engaged with the loop and an eye at the other end so that the device may be hung up.

In testimony whereof I affix my signature.

FREDERICK J. LAU, SR.
